2 Claims

ABSTRACT OF THE DISCLOSURE

New basic esters are provided which are useful in the palliative treatment of Parkinsonism. The new esters have the formula:

wherein

R_1 is phenyl or cyclohexyl,
 R_2 and R_3 are different lower alkyl groups of 1 to 6 carbon atoms, and
 X is divalent alkylene of 2 or 3 carbon atoms,
and non-toxic pharmaceutically acceptable acid addition salts thereof, and are produced from a substituted acetic acid ester of the formula:

which is reacted with an N-disubstituted aminoalcohol of the formula:

wherein R_1 , R_2 , R_3 and X have the above meanings, to produce the new and useful compounds of Formula I.

The present invention relates to new basic esters useful for the palliative treatment of Parkinsonism and the present application is a continuation of application Ser. No. 732,517, filed May 28, 1968, now abandoned, which is a continuation-in-part of application Ser. No. 390,173, filed Aug. 17, 1964, now abandoned.

The new anti-Parkinson compounds of the present invention have the formula:

wherein

R₁ is phenyl or cyclohexyl,
 R₂ and R₃ are different lower alkyl groups of 1 to 6 carbon atoms, and
 X is divalent alkylene of 2 or 3 carbon atoms,

2

and non-toxic pharmaceutically acceptable acid addition salts thereof, and in particular the hydrochloride. These compounds exhibit a high anti-tremorine activity in tests on animals and in other tests as set forth below. Particularly good compounds are those wherein R_1 is phenyl or cyclohexyl, R_2 is ethyl and R_3 is n-propyl with X being $-\text{CH}_2\text{CH}_2-$. These compounds also are characterized by unexpectedly low anti-acetylcholine activity in contrast to what might have been predicted from existing knowledge in this art and consequently the new compounds are free from the adverse side effects usually associated with presently available commercially employed anti-Parkinson compounds.

The dosage and route of administration of the new anti-Parkinson compounds are in general the same as with known anti-Parkinson compounds. It is well recognized, however, that the dosage of active drug used for the treatment of Parkinsonism varies considerably from patient to patient and depending upon the severity of the condition existing in each patient as well as the length of time during which the patient has been affected with Parkinsonism. It is thus not possible to make a general rule with respect to amount and frequency of dosage as the physician or clinician must use his own best judgment. It is, however, customary to start a patient on a relatively small amount and then gradually or incrementally to increase the dosage until signs of toxicity begin to become apparent as the maximal dosage or maintenance dosage should thereafter be below that amount which causes toxic reactions and yet which is sufficient to be effective in the treatment of the particular patient, it being noted that the present compounds are like other anti-Parkinson compounds intended only as palliative, because there is presently no known cure for Parkinsonism. The literature and scientific information readily provides dosages used for other and less desirable and less effective anti-Parkinson compounds as compared with the present invention.

The new esters prepared by reacting a substituted acetic acid ester of the formula:

with an **N**-disubstituted aminoalcohol of the formula:

wherein R₁, R₂, R₃ and X have the meanings set forth above. The reaction is preferably but not necessarily carried out in the presence of a catalyst which is an alkali or alkaline earth metal alkoxide. Sodium methoxide is a particularly good catalyst. The reaction is preferably carried out by heating the reactants II and III in a solvent such as light petroleum or n-heptane and the catalyst may be and usually is dissolved in a suitable solvent such as a sodium alkoxide which is present in excess of the corresponding alkanol. The substituted acetic acid esters of Formula II, which are used as the starting materials for the new compounds I, are prepared according to methods known per se.

Tests for pharmacological activity have been carried out on two of the compounds of the present invention together with comparative tests on compounds of similar structure. The compounds tested were the hydrochlorides

of the following bases but wherein R_2 and R_3 are identical and non-identical:

Compounds I and II are the compounds of Examples 1 and 2, respectively, and compound V is described in U.S. Pat. No. 2,399,736. Compound III is the drug Benactyzine.

Initially, the toxicities of compounds I to VI were determined in mice. Groups of 5 mice were each injected subcutaneously with solutions of compounds I, II, IV, V and VI and intravenously with a solution of compound III, and they were observed for toxic symptoms over a period of 24 hours. The number of animals that died in each group was noted and the LD_{50} (the median lethal dose), in mg./kg. body weight, was calculated. The results were as follows:

Compound:	LD_{50} mg./kg.
I	200
II	1000
III	31
IV	300
V	200
VI	2500

The anti-tremorine activity of compounds I to VI was determined by dosing groups of 5 mice subcutaneously with a solution of each compound. After 30 minutes the mice were challenged with 40 mg./kg. of tremorine administered intraperitoneally and the mice were assessed after a further 30 minutes for tremor. The degree of inhibition of tremor due to the tremorine was used to calculate the ED_{50} (medium effective dose), and the results were as follows:

Compound:	ED_{50} mg./kg.
I	5.0
II	5.6
III	3.8
IV	4.2
V	5.0
VI	10

The mydriatic activity of compounds I and VI in mice was determined by dosing groups of 5 mice subcutaneous-

ly with a solution of each compound. After 20 minutes the eyes of the mice were inspected under a binocular microscope and the degree of mydriasis was measured in orbitary units by using a scale in one eyepiece. The results were used to determine the ED_{50} and were as follows:

Compound:	ED_{50} mg./kg.
I	26
II	7.5
III	0.5
IV	0.6
V	0.25
VI	12.5

The effect of compounds I and VI on the central nervous system was determined by measuring their inhibiting action in preventing convulsions due to the application of a maximal electroshock (MES) to the brain of mice. Groups of 10 mice were injected subcutaneously with solutions of the compounds, then subjected to an MES one hour later. The mice used had been preselected for their ability to exhibit maximum seizure before the active compound was administered. The ED_{50} values for compounds I and II were 6.8 and 50 mg./kg., respectively, whereas compounds III to VI showed no inhibition of the MES.

From the results of the tests described above it is shown that useful anti-tremorine activity was exhibited in mice at doses below the mydriatic dose for compounds I and II, whereas for compounds III to VI the mydriatic activity was evidenced at doses well below anti-tremorine effects. Furthermore, in the described tests, compounds I and II showed anti-convulsant activity, as evidenced by inhibition of MES seizures in mice, whereas compounds III to VI did not show such activity. This distinguished compounds I and II from compounds III to VI and indicated the usefulness of compounds I and II in the treatment of Parkinson tremor and rigidity.

Further tests were made to compare compound I with Benzhexol, which is one of the main drugs used throughout the world in the treatment of Parkinsonism. Compound I and Benzhexol were administered subcutaneously and perorally to groups of 20 mice, then after 20 minutes 2 mg./kg. of oxotremorine was administered intraperitoneally.

The doses of both compounds required to prevent tremor were determined after a further 10 minutes, and the ED_{50} values were calculated. The mydriatic activities and toxicities for the two compounds were determined subcutaneously in mice as described previously and perorally by similar methods; groups of 10 mice were used for these determinations. The results were as follows:

Compound:	Compound I		Benzhexol	
	Subcutaneous	Peroral	Subcutaneous	Peroral
Anti-oxotremorine	4.8	38	5.0	30
Mydriatic	26	50	0.7	5.5
LD_{50}	400	500	640	750

In the tests oxotremorine was used since tremors are produced quickly, whereas if tremorine is used, it has to be converted in vivo to oxotremorine to produce tremors. The results of the tests indicated that Benzhexol could not be administered in sufficiently high dose to produce its full effect without the onset of atropine-like side effects (mydriatic activity, dryness of mouth, etc.), whereas compound I produced its full effects at doses that did not cause these side effects.

Atropine is not used in the regular treatment of Parkinsonism as the side effects are such that it would cause undue distress and hospitalization of the patient if used in therapeutic doses for the treatment of this condition.

The invention is illustrated by the following nonlimitative examples.

5

EXAMPLE 1

Preparation of 2-(ethylpropylamino)ethyl α, α -diphenylglycolate hydrochloride

A methanolic solution of sodium methoxide (from sodium (0.2 g.) and dry methanol (3 ml.) was added dropwise during 20 minutes to a boiling solution of methyl α, α -diphenylglycolate (11 g.) and 2-ethylpropylaminoethanol (6 g.) in light petroleum (150 ml., B.P. 80–100°) and the methanol that separated was removed by using a Dean and Starke apparatus. At the end of 5 hours no further separation of methanol occurred and the reaction mixture after being washed with water (3×20 ml.) was extracted with 1 N hydrochloric acid (3×30 ml.)

The acid extracts (after washing with ether (50 ml.) were made alkaline with aqueous 5 N sodium hydroxide solution, the liberated base was extracted into ether (4× 50 ml.) and the ether extracts were dried (MgSO_4). Treatment of the extracts with hydrogen chloride gave the hydrochloride (11 g., 70%), which was obtained as rectangular plates, M.P. 164 to 166° C., after several

crystallizations from butanone (Found: C, 67.0; H, 7.6; Cl, 9.4. $C_{21}H_{28}ClNO_3$ requires: C, 66.7; H, 7.5; Cl, 9.4%).

6

crystallizations from butanone (Found: C, 67.0; H, 7.5; Cl, 9.4. $C_{21}H_{28}ClNO_3$ requires: C, 66.7; H, 7.5; Cl, 9.4%).

10 A methanolic solution of sodium methoxide [from sodium (0.2 g.) in dry methanol (3 ml.)] was added dropwise during 20 minutes to a boiling solution of methyl α -cyclohexyl- α -phenylglycolate (16 g.) and 2-ethylpropylaminoethanol (12.7 g.) in light petroleum (500 ml., B.P. 80-100°). The reaction mixture was then treated as described in Example 1 to give the hydrochloride (16.6 g., 67%), as colorless needles, M.P. 200 to 201° C., after crystallization from ethanol. (Found: C, 65.3; H, 9.0; Cl, 9.0. $C_16H_{21}ClNO_2$ requires C, 65.6; H, 8.9; Cl, 9.0.)

20 Esters of the following formula were prepared similarly (Ph, Me, Et, Pr and Bu stand for phenyl, methyl, ethyl, propyl and butyl, respectively):

Example No.	R ₁	Y	M.P. (° C.)	Yield, percent	Analysis
3	Ph		148-150	73	$C_{19}H_{21}ClNO_3 = 349.9$ Found: C=65.4; H=7.2; Cl ⁻ =10.3%. Requires: C=65.2; H=6.9; Cl ⁻ =10.1%.
4	Cyclo-C ₆ H ₁₁	Same	192-193	34	$C_{19}H_{20}ClNO_3 = 355.9$ Found: C=64.0; H=8.5; Cl ⁻ =10.1%. Requires: C=64.1; H=8.5; Cl ⁻ =10.0%.
5	Ph		151-153	62	$C_{20}H_{23}ClNO_3 = 363.9$ Found: C=65.7; H=7.3; Cl ⁻ =9.8%. Requires: C=66.05; H=7.2; Cl ⁻ =9.7%.
6	Cyclo-C ₆ H ₁₁	Same	189-191	90	$C_{20}H_{22}ClNO_3 = 369.9$ Found: C=65.3; H=9.1; Cl ⁻ =9.6%. Requires: C=64.9; H=8.7; Cl ⁻ =9.6%.
7	Ph		154-156	56	$C_{21}H_{25}ClNO_3 = 377.9$ Found: C=66.5; H=7.6; Cl ⁻ =9.6%. Requires: C=66.7; H=7.5; Cl ⁻ =9.4%.
8	Ph		148	39	$C_{21}H_{24}ClNO_3 = 377.9$ Found: C=66.5; H=7.8; Cl ⁻ =9.6%. Requires: C=66.7; H=7.5; Cl ⁻ =9.4%.
9	Cyclo-C ₆ H ₁₁	Same	185-186	73	$C_{21}H_{23}ClNO_3 = 384.0$ Found: C=65.4; H=9.2; Cl ⁻ =9.4%. Requires: C=65.7; H=8.9; Cl ⁻ =9.2%.
10	Ph		134-134	68	$C_{22}H_{29}ClNO_3 = 392.0$ Found: C=67.4; H=8.05; Cl ⁻ =9.3%. Requires: C=67.4; H=7.7; Cl ⁻ =9.05%.
11	Cyclo-C ₆ H ₁₁	Same	170-171	65	$C_{22}H_{28}ClNO_3 = 398.0$ Found: C=66.7; H=9.35; Cl ⁻ =9.05%. Requires: C=66.4; H=9.1; Cl ⁻ =8.9%.
12	Ph		161-163	80	$C_{22}H_{29}ClNO_3 = 392.0$ Found: C=67.7; H=7.6; Cl ⁻ =9.0%. Requires: C=67.4; H=7.7; Cl ⁻ =9.05%.
13	Cyclo-C ₆ H ₁₁	Same	181-182	74	$C_{22}H_{28}ClNO_3 = 398.0$ Found: C=66.6; H=9.0; Cl ⁻ =8.8%. Requires: C=66.4; H=8.1; Cl ⁻ =8.9%.
14	Ph		143-145	67	$C_{22}H_{29}ClNO_3 = 392.0$ Found: C=67.1; H=7.9; Cl ⁻ =9.05%. Requires: C=67.4; H=7.7; Cl ⁻ =9.05%.
15	Cyclo-C ₆ H ₁₁	Same	151-153	23	$C_{22}H_{28}ClNO_3 = 398.0$ Found: C=66.1; H=9.1; Cl ⁻ =9.00%. Requires: C=66.4; H=9.1; Cl ⁻ =8.9%.

EXAMPLE 16

Preparation of 3-(ethylpropylamino)propyl α,α -diphenylglycolate hydrochloride

3-(ethylpropylamino)propan-1-ol (6 g.) and methyl α,α -diphenylglycolate (12.5 g.) in boiling heptane (250 ml.) were treated with a methanolic solution of sodium methoxide [from sodium (0.1 g.) and dry methanol (3 ml.)]. The reaction mixture was worked up as in Example 1 and the ether extracts, after drying ($MgSO_4$), on treatment with ethereal hydrogen chloride gave the hydrochloride (12.8 g.; 80%), which was obtained as colorless prisms, M.P. 152-152.5°C. after crystallization from isopropanol (Found: C, 67.7; H, 7.9; Cl, 8.9. $C_{22}H_{30}ClNO_3$ requires: C, 67.4; H, 7.7; Cl, 9.1%).

EXAMPLE 17

Preparation of 3-(ethylpropylamino)propyl α -cyclohexyl- α -phenylglycolate hydrochloride

3-(ethylpropylamino)propan-1-ol (6 g.) and methyl α -cyclohexyl- α -phenylglycolate (12.8 g.) in boiling heptane (250 ml.) were treated with a methanolic solution of sodium methoxide [from sodium (0.1 g.) and dry methanol (3 ml.)]. Treatment of the dried ethereal solution obtained as described in Example 16, with ethereal hydrogen chloride gave the hydrochloride (11.5 g., 70%), as colorless prisms, M.P. 145-146°C. after crystallization from isopropanol (Found: C, 66.4; H, 9.3; Cl, 9.1. $C_{22}H_{30}ClNO_3$ requires: C, 66.4; H, 9.1; Cl, 8.9%).

The parent alcohol 3-(ethylpropylamino)propan-1-ol was obtained as follows:

Ethyl acrylate was added dropwise with stirring to an excess of n-propylamine (600 g.) containing water (10 ml.) and allowed to stand at room temperature for 4 hours. After removal of excess of propylamine, the residual oil was dissolved in ether, dried ($MgSO_4$), the solvent removed by evaporation and the liquid distilled under reduced pressure to give ethyl β -n-propylaminopropionate (136 g., 86%) as a colorless liquid, B.P. 78°C./9 mm., n_D^{20} 1.4258. This was then acetylated with acetic anhydride to give ethyl β -(n-propylacetylamino)propionate as a colorless oil (160 g.; 93%), B.P. 104°C./0.6 mm., n_D^{20} 1.4526. The latter on reduction with lithium aluminum hydride in ether yielded the desired 3-(ethylpropylamino)propan-1-ol (77.5 g.; 67%), B.P. 82.5°C./10 mm., n_D^{20} 1.4422.

It is to be particularly noted that R_2 and R_3 cannot be identical and it is of critical significance that they be different lower alkyl groups as exemplified by the foregoing examples. It is only when R_2 and R_3 are different lower alkyl groups that the full benefit and utility of the new compounds is realized for the treatment of Parkinsonism. Compounds are known of similar constitution to the compounds of this invention but where the dialkylamino moiety has two like alkyl groups such as diethylamino or dipropylamino. Such compounds do not have anti-Parkinson utility, but on the contrary, may have utility as mere tranquilizers. It is, therefore crucial with respect to the present invention that the lower alkyl groups of the dialkylamino moiety of the new compounds of this invention have different lower alkyl groups and an important aspect of the present invention resides in the discovery that these alkyl groups must be different, because if they are not different, the resulting compounds have properties and usefulness for purposes other than the treatment of Parkinsonism. It is further vitally important that the effective dose of the new compounds of the present invention is below that which causes mydriasis whereas such is not true of substances heretofore used in the treatment of Parkinsonism and wherein some effectiveness can be attained only by the use of such large dosages as to cause adverse unpleasant and even serious side effects such as blurred vision, dry mouth and symptoms of mydriasis.

What is claimed is:

1. A compound selected from the group consisting of 2-(ethylpropylamino)ethyl- α,α -diphenylglycolate and the hydrochloride thereof.

2. The hydrochloride of the compound of claim 1.
